UNITED STATES PATENT OFFICE.

JESSE LEE RAYMAN, OF LOUISVILLE, KENTUCKY.

WORK-HOLDING STAND.

1,286,408.

Specification of Letters Patent.

Patented Dec. 3, 1918.

Application filed May 13, 1918. Serial No. 234,108.

To all whom it may concern:

Be it known that I, JESSE LEE RAYMAN, a citizen of the United States, residing at Louisville, in the county of Jefferson and State of Kentucky, have invented certain new and useful Improvements in Work-Holding Stands, of which the following is a specification.

The work-holding stand which is the subject matter of the present application for patent is designed more particularly for providing a simple and handy means for securely holding the cylinder block of a Ford motor in several different positions to facilitate repairs thereto, it being understood however that the device can, with slight modifications, be employed also for supporting other makes of blocks.

In order that the invention may be better understood reference is had to the accompanying drawing forming a part of this specification, in which drawing—

Figure 1 is a side elevation of the stand; Fig. 2 is a plan view thereof, and Fig. 3 is an end view.

The preferred embodiment of the invention has been illustrated, but it is to be understood that various changes and modifications in the structure may be made without a departure from the spirit and scope of the invention as claimed hereinafter.

Referring now specifically to the drawing, 5 denotes a pair of laterally spaced base members which are rigidly fastened down by screws or other suitable means 6, to the top of a work bench or other convenient support, a fragment of which is shown at 7. The top of each base member has an upstanding flange 8 for a purpose to be presently described, the flange at one end of the member being shaped to form a prop or post 9.

The base members 5 pivotally support a circular track 10 having two pairs of depending flanges 11 on its under side, which 45 straddle the flanges 8, with pivot pins 12 passing through said flanges to provide the pivotal connection. As the pivot pins 12 are horizontal, the track 10 is supported to swing in a vertical plane. The normal position of the track is horizontal, in which 50 position its end opposite the pivot or hinge connection rests on the posts 9.

Concentric with the pivots 12, the flanges 11 have a series of apertures 13 which are 55 adapted to aline with apertures 14 in the flanges 8, so that by passing pins 15 there-

through the track 10 can be located and held at different angles.

The track 10 supports a saddle having means for holding the cylinder block to be 60 operated on, the same being shown at C. This saddle is in the shape of a rectangular frame composed of side walls 16 and end walls 17. The top of the saddle is shaped to form a seat for the cylinder block, 65 the latter being placed on its side, so that its top is adjacent to one end wall 17, and its bottom is adjacent to the other end wall. The Ford cylinder block has a bottom flange C¹ for attachment of the crank case, and the 70 top of the block is tapped, as shown at C² for cap screws which fasten down a removable head. The flange C¹ has bolt holes C³. The openings C² and C³ are utilized for securing the block to the saddle, it being understood, of course, that the cylinder head and the crank case are first removed. The 75 top of the saddle is shaped to conform to the sides of the block, and when the latter is placed on the saddle, the flange C¹ extends along one of the end walls 17 from which latter project pins or studs 18 to enter the bolt holes C³. The opposite end wall 17 carries two screw bolts 19 which are positioned to be screwed into two of the openings C², 80 which completes the fastening of the block down on the saddle. The bolts 19 are kept 85 in position, ready for use, by flat springs 20.

The saddle hereinbefore described is rotatably connected to the track 10, so that it 90 may be swung around in a horizontal plane to place the block C in the most convenient position for the work to be done thereon. This connection is made by bolts 21 passing loosely through an annular slot 22 in the track 10 from the bottom of the latter, and 95 screwed into the bottom of the walls 16 and 17. The flanges 11 are recessed, as shown at 23, to accommodate the heads of the bolts 21 when the saddle is rotated on the track.

The device provides a simple and handy support for the cylinder block, and the latter can be readily positioned in many different positions so that the work can be conveniently and easily done. Fig. 1 shows in 100 dotted lines one position to which the block may be swung, and as it is also rotatable, all the parts are readily accessible for the necessary work to be done thereon. For a different make of cylinder block it is necessary only to provide a saddle adapted to the 105 particular block to be supported.

I claim:

1. A work - holding stand comprising a work holder, a support for the holder having a circular slot, means for fastening the holder to the support for rotary movement thereon; said means passing through the slot, a base to which the support is pivoted to swing in a plane at a right angle to the plane in which the holder is rotatable, and 10 a prop rising from the base and engageable with the free end of the support.

2. A work - holding stand comprising a work holder, a support on which the holder is rotatably mounted, a base to which the support is pivoted to swing in a plane at a 15 right angle to the plane in which the holder is rotatable, and a prop rising from the base and engageable with the free end of the support.

In testimony whereof I affix my signature. 20

JESSE LEE RAYMAN.
